UNITED STATES PATENT OFFICE.

JOHN T. RICHARDSON, OF HARRISBURG, ASSIGNOR OF ONE-HALF TO ALEXANDER H. EGE, OF MECHANICSBURG, PENNSYLVANIA.

BINDING-BAR.

SPECIFICATION forming part of Letters Patent No. 404,865, dated June 11, 1889.

Application filed October 20, 1888. Serial No. 288,637. (No model.)

To all whom it may concern:

Be it known that I, JOHN T. RICHARDSON, of Harrisburg, in the county of Dauphin and State of Pennsylvania, have invented certain new and useful Improvements in Binding-Bars for Spring Railway-Frogs; and I do hereby declare that the following is a full, clear, and exact statement and description of the invention, which will enable others skilled in the art to which it appertains to make and use the same, reference being had to the accompanying drawings, and to letters of reference marked thereon, which form a part of this specification.

15 My invention relates to railway-frogs; and it consists, specifically, in the construction of binding bars or clamps for railway spring-frogs by which I secure a most efficient mode of binding the tongue of the frog to the rigid rail thereof, (the ordinary filling and side supporting-blocks being used for spacing purposes,) said binding-bars passing under the rails and being held thereto securely, as hereinafter more fully set forth.

25 In the drawings, Figure 1 is a plan view of a spring-frog provided with my improvement. Fig. 2 is a transverse section on the line X X of the binding-bar nearest to the heel of the frog with the guide in place. Fig. 3 is a 30 vertical section on the line Y Y of the binding-bar supporting the apex of the tongue. Fig. 4 shows the locking-lug detached. Fig. 5 is a perspective view of one of the bearing and binding bars or plates.

35 In the drawings, A designates the fixed or rigid wing-rail of the frog, B the movable wing-rail, and C the tongue of the frog formed by the converging rails D.

The spring inclosed in the housing E is of 40 ordinary construction, and operates when at rest to hold the movable rail in lateral contact with the tongue of the frog while it admits of contraction under the conditions of shunting. The bearing and binding bars or 45 plates F and F' pass beneath the frog and wing-rails, the former near the heel and the latter near the point of the frog. The ends b and b' of these bars adjacent to the fixed rail are turned upward, so as to support the 50 side spacing-blocks a a', and are perforated

for the purpose set forth in full in Letters Patent granted to me October 20, 1885, No. 328,810, in the manner therein described. The opposite end of the binding-bar F' is turned upward to constitute a stop c to limit the outer 55 lateral movement of the movable wing-rail B when the latter is forced away from the contact with the tongue C by means of the wheel-flanges of a shunted train. Said binding-bars are perforated at d d' at or about their 60 longitudinal centers for the reception of the smaller ends e of the locking-lugs f. The binding-bar F', differs at its end next to the movable wing-rail from the corresponding end of the bar F, as shown in Fig. 5, on account of its function in supplying a bearing- 65 surface to which the guide g of the movable rail is bolted.

The lugs f, as shown in Fig. 4, are recessed or shouldered on their vertical lateral edges 70 to form an expanded head, a reduced stem part e, and an intermediate portion, it having two shoulders s s' on each edge, the shoulder s to rest when the lugs are in position on the horizontal upper surface of the binding-bars, 75 and the shoulder s' on the flange of the tongue C. The projecting stem ends e of the lugs f are shaped to fit accurately into the elongated holes d d', and are riveted or otherwise securely fastened therein, but preferably by 80 means of the keys k.

The clamps or binding-bars being put into place and the lugs f made to fit into their respective seats i in the flange of the tongue-rail C, are forced tightly thereinto by the 85 binding key-blocks a a' on the outer side of the rigid wing-rail, all the stationary parts of the frog being bound securely together. The shoulders s' of the lugs f prevent the binding-bars F F' from dropping downward from 90 any cause whatever. The lug f in the binding-bar F is perforated from its outer vertical surface to receive the smaller inner end of the guide g, the opposite end l thereof being bolted to the underlying free end of the binding-bar F. 95

It will also be seen when the guide g is in position that it passes through an elongated aperture in the vertical web of the movable wing-rail B, thereby, while admitting a free 100

lateral movement of the same, retaining it in the proper plane of movement at all times, and thus overcoming all tendency to tilting or rising thereof. The downward curve of 5 the guide *g* performs the important function of a stop to limit, in connection with the outer flanged end *c* of the binding-bar *F'*, the outer lateral motion of the movable wing-rail *B*. Upon examination it is seen that an additional 10 advantage is gained by the horizontal extension of the binding-bars from the fact that frictional bearing-surfaces for the support of the movable wing-rail *A* are thereby secured, and all the parts of the frog are retained in the same plane.

Having thus described my invention, what I claim, and desire to secure by Letters Patent, is—

1. In a railway-frog, the combination, with 20 the tongue-rails, one of which has a notched flange, of the bearing-plate upon which the said rails rest, and the locking-lug having an expanded head resting upon the said rail-flange and also resting in the notch therein 25 and secured to the said plate, substantially as set forth.

2. In a railway spring-frog, the combination of the tongue-rails, the fixed wing-rail secured to the tongue-rails, the movable wing-rail, the bearing-plate beneath the said rails, and a 30 lug secured to the said plate situated between the movable wing-rail and the adjacent tongue-rail, and having an expanded head engaging with the flange of the tongue-rail, substantially as set forth. 35

3. The combination, with the tongue-rails and the wing-rails, of the bearing-plates below the said rails, and the locking-lugs *f*, having shouldered edges, seated in notches in the flange of the tongue-rail and passing through 40 the said plates, to which they are secured by keys, substantially as set forth.

In testimony whereof I have signed my name to this specification in the presence of two subscribing witnesses.

JOHN T. RICHARDSON.
